[57] CLAIM

The ornamental design for a football penalty flag, as shown and described.

DESCRIPTION

FIG. 1 is a top plan view of a football penalty flag showing our new design in the opened position; and FIG. 2 is a side elevational view thereof showing the design in alternate condition. The side opposite being a mirror image.

The unshown bottom of the design is substantially plain and unornamented.

FIG. 2
